SWITCH AND SIGNAL CONTROL SYSTEM
FOR RAILROADS

Sedgwick N. Wight, Rochester, N. Y., assignor to
General Railway Signal Company, Rochester,
N. Y.

Application May 26, 1939, Serial No. 275,923

30 Claims. (Cl. 246—134)

This invention relates to interlocking systems for railroads, and it more particularly pertains to an interlocking system of the entrance-exit type now Patent No. 2,219,502 granted October 29, 1940.

This application is a continuation in part of the prior application Ser. No. 245,384, filed December 13, 1938.

The entrance-exit type interlocking system provided by this invention is also to be considered as an improvement over prior applications of A. Langdon, Ser. No. 119,641, filed January 8, 1937, and Patent No. 2,148,865, dated February 28, 1939, and no claim is made herein to subject matter disclosed in those applications.

In governing traffic over complex track layouts by the entrance-exit system for controlling track switches and signals, an operator in a control office can cause the setting up of each of the various routes by actuating a control button on a control panel for each end of each route desired to be set up. The control buttons are generally located on a miniature track diagram on the control panel which corresponds to the track layout for which the interlocking system is provided. The relative location of the buttons on the miniature track diagram corresponds to the relative location of the signals of the track layout.

To facilitate the disclosure of the present invention, each group of track switches providing routes between entrance and exit points between which no intermediate signals are included, is conveniently called an interlocked group. Thus, in setting up a route from one end of the interlocking plant to the other past intermediate signals, the complete route set up extends through a plurality of interlocked groups. The setting up of a route extending through a plurality of interlocked groups by actuation of the control buttons for the extreme ends only for that route, is conveniently called end-to-end or through route control.

When an entrance point is designated by the actuation of a button for that point, in accordance with the entrance-exit system disclosed in the above mentioned Langdon disclosures, route selector relays are so positioned for each track switch included in each possible route emanating from that point, that those relays select the pick-up circuits for switch control relays for the various track switches in such a manner that the actuation of a button for the exit point for any one of those routes causes the proper positioning of the track switches for setting up a

route between the designated entrance and exit points. In other words, the route selector relays are positioned in response to the actuation of the button for the entrance point, and the switch control relays are positioned, in accordance with their pick-up circuits selected by the route selector relays, in response to the actuation of the button for the exit point. Route selector relays are picked up only for track switches that are trailed by traffic in the designated direction. The circuits are so interlocked that no route can be set up which conflicts with a route already established.

One object of the present invention is to provide an entrance-exit interlocking system having end-to-end control in which the relays for setting up a route through each interlocked group are automatically restored to normal upon passage of a train. In response to the actuation of an entrance button, the route selector relays are positioned for each track switch included in each possible route emanating from that point, irrespective of the number of interlocked groups included in each route. In response to the actuation of an exit button for one of those routes, the switch control relays, forming a completion network, are positioned in accordance with their pick-up circuits as selected or pre-conditioned by the route selector relays. The switch control relays are picked up successively, starting with the relay for the track switch nearest the exit point designated; and the response of the completion network for each interlocked group causes the picking up of an entrance relay for that group, that relay being maintained picked up dependent upon the passage of a train or manual restoration. The picking up of such an entrance relay provides pick-up energy for the next exit relay toward the entrance relay for the designated entrance point. Thus, the completion network builds up through each interlocked group until the switch control relays are positioned for the entire through route between the designated entrance and exit points.

Another object of this invention is to provide means by which any particular one of several optional routes can be predetermined to be preferred. Such preference is required in practice, for example, where a high speed track switch common to several routes is desired to be used when available, in preference to lower speed track switches providing optional routes.

Such preferred routes are selected in accordance with the control circuits for the route selector relays. That is, it can be predetermined

that a route selector relay for each track switch is to be picked up only when that track switch must be normal for the route initiated. If the circuits are provided in this manner, the optional route diverging nearest the entrance point is given preference. It can be predetermined that a route selector relay for each track switch is to be picked up only when that track switch must be reverse for the route thus initiated. If the circuits are provided in this manner, the optional route diverging nearest the exit point is given preference. Thus, by providing that the route selector relays are picked up when their track switches are to be normal, or when their track switches are to be reverse, or some combination of normal and reverse selection, it is possible in practice to predetermine that preference is given to any particular one of several optional routes.

Where a track switch is included in a reverse position in a preferred route emanating from a particular entrance point, and that track switch is included in a normal position in a preferred route emanating from another entrance point, for traffic in the same direction, an auxiliary route selector relay is used in order to provide the desired preference for setting up routes associated with each of those entrance points.

A further object of this invention is to provide a limitation of the end-to-end control in such a manner that an operator can set up any route by end-to-end operation, except a particular route which would allow a train to leave the interlocking plant against the normal direction of traffic. To set up that particular route against the normal direction of traffic an operator must actuate the entrance and exit control buttons for the particular interlocked group at that end of the interlocking plant. Thus, the chance of an operator inadvertently sending a train out of the interlocking plant against the normal direction of traffic because of the actuation of the wrong exit button, is reduced to a minimum.

Other objects, purposes and characteristic features of the present invention will be in part obvious from the accompanying drawings, and in part pointed out as the description of the invention progresses.

In describing the invention in detail, reference will be made to the accompanying drawings, in which like reference characters designate corresponding parts throughout the several illustrations, similar letter reference characters being used to designate parts of a similar nature which are generally made distinctive by preceding numerals, and in which:

Figs. 1A, 1B and 1C, when placed side by side above Figs. 1D, 1E and 1F respectively, illustrate the self-selecting network provided for this particular embodiment of the present invention;

Fig. 2 illustrates certain typical circuits relative to the track switch and signal controls; and

Figs. 3A and 3B, when placed side by side, illustrate the track layout and signal controls for this embodiment of the present invention.

In considering various parts of a similar nature from time to time during the disclosure, reference is made in a general manner to those parts by letter reference characters without their preceding numerals. It is to be understood that such a reference applies to any parts designated in the drawings by reference characters that are similar except for numerals associated therewith.

The various parts and circuits constituting the embodiment of the present invention have been

shown diagrammatically and certain conventional illustrations have been employed for the purpose of simplifying the illustration and facilitating in the explanation of the invention. The drawings are made more for the purpose of facilitating the disclosure of the invention as to the principles involved and the mode of operation, than for the purpose of illustrating the specific construction and arrangement of parts that would be employed in practice. Thus, the various relays and their contacts together with control buttons and other apparatus are illustrated in a conventional manner, and symbols are used to indicate connections to the terminals of batteries or other sources of electric current instead of showing all of the wiring connections to those terminals.

The symbols (+) and (-) are employed to indicate the positive and negative terminals respectively of suitable batteries, or other sources of direct current; and the circuits with which those symbols are used always have current flowing in the same direction. If alternating current is used instead of direct current, the symbols should be considered to represent the instantaneous relative polarities applied to the circuits. It is to be understood that certain of the various circuits can be energized from a common battery and that several batteries can be provided where required in practice.

To facilitate in the disclosure of the present invention, various relays and circuits are shown in duplicate on various pages of the drawings, and those relays and circuits shown having corresponding reference characters are to be considered identical.

Apparatus

Track layout.—With reference to Figs. 3A and 3B, two parallel tracks have been illustrated as connected together at various points by crossovers having track switches 2TSA, 2TSB, 3TSA, 3TSB, 4TSA and 4TSB.

The track switches are positioned by power operated switch machines which can be of any suitable type such, for example, as the switch machine shown in the patent to W. K. Howe, Patent No. 1,466,903, dated September 4, 1923. The motors of the switch machines can be controlled in any suitable manner, such, for example, as in the patent to W. H. Hoppe et al., Patent No. 1,877,876, dated September 20, 1932. If the switch machine motors are controlled in accordance with that Hoppe et al. patent, the relay CR of that patent is controlled by the relay WZ illustrated in Fig. 2 of the present disclosure.

In order to simplify the present disclosure only one switch machine SM has been shown for each crossover, because the track switches for both ends of the crossovers should always assume corresponding positions. Thus, switch machine 2SM has been provided for positioning track switches 2TSA and 2TSB, switch machine 3SM has been provided for positioning track switches 3TSA and 3TSB and switch machine 4SM has been provided for positioning track switches 4TSA and 4TSB. It is to be understood that a separate switch machine SM can be provided for governing each track switch in accordance with the requirements of practice.

A polar neutral relay WP is provided for each crossover for repeating the locked position of the track switches in correspondence with the locked position of the switch machine. That is, relay 2WP, for example, is energized with one polarity when the switch machine 2SM is in a normal

locked position and the track switches 2TSA and 2TSB are locked normal, and that relay is energized with the opposite polarity when switch machine 2SM is in a reverse locked position and track switches 2TSA and 2TSB are locked reverse. Relay 2WP is dropped away whenever either of the two above conditions are not completely satisfied. The control circuits for the relays WP are selected to provide such a mode of operation by point detector contact mechanisms such as the type shown, for example, in the patent to C. S. Bushnell, Patent No. 1,517,236, dated November 25, 1924.

Signals 10, 11, 14 and 15 have been provided for governing east bound traffic, to the right, and signals 12, 13, 16 and 17 have been provided for governing west bound traffic, to the left.

The signals have been illustrated as being of the searchlight type. The searchlight type signals can be of a type such as is shown, for example, in the patent to O. S. Field, Patent No. 1,835,150, dated December 12, 1931. Each of the signals illustrated in this disclosure is provided with contacts closed only when the signal is at stop, as shown in that Field patent, for energizing a signal at stop repeater relay M associated with that signal. The signals are considered to provide a normal-at-stop red indication and a clear green indication. It is also to be understood that a yellow indication for caution can be provided if such indication is required in practice, and that other types of signals could as well be employed in accordance with the present invention, such, for example, as signals having individual color lamp units or signals of the semaphore type.

The track layout has been divided into track sections by the usual insulated joints to provide the usual track circuits for the track relays. Track sections 6, 7, 8 and 9 have been shown as having associated therewith track relays 6T, 7T, 8T and 9T respectively. Slow acting track repeater relays 6TP, 7TP, 8TP and 9TP are provided for track relays 6T, 7T, 8T and 9T respectively. It is of course to be understood that the number of track circuits can be varied in accordance with the requirements in practice from the particular track circuit arrangement illustrated in the present disclosure. The track circuits are assumed to be of the usual normally energized type, and the track switches are assumed to be properly bonded to provide fouling protection, all of which details have not been shown in order to simplify the present disclosure, because those details are well known to those familiar with the art.

Control machine.—The control machine provided for governing traffic through the track layout heretofore described, has a control panel upon which is constructed a miniature track diagram (see Figs. 1A, 1B and 1C) corresponding to that track layout. The miniature track diagram is provided with suitable indication means along the diagram sections representative of the track sections and track switches to provide necessary indications with respect to routes that have been established, the presence of trains on the sections, and the indication of the signals at the various points in the track layout. Inasmuch as this invention relates more particularly to the use of a self-selecting network in setting up the various routes, those indications have not been shown. Such indications can be provided as shown and described in the prior Hitchcock application, Ser. No. 74,709, filed April 16, 1936, and in the patent

to A. Langdon, Patent No. 2,148,865, dated February 28, 1939.

An entrance button NB is provided on the miniature track diagram for the entrance point to each route as defined at the track layout by the location of the signals. Thus, buttons 10NB, 11NB, 12NB, 13NB, 14NB, 15NB, 16NB and 17NB have been provided on the control panel as representative of entrance points at signals 10, 11, 12, 13, 14, 15, 16 and 17 respectively. The buttons are located on the miniature track diagram at positions corresponding to the positions of the signals at the track layout for governing entrance at those entrance points. Each entrance button NB is of the push-pull button type. That is, the button is biased to a normal position from which it can either be depressed or pulled out. There is an operating contact on the button which is closed when the button is depressed, and there is a normally closed contact on the button which is closed when the button is in its normal position as well as when it is depressed. When the button is pulled out, the normally closed contact is opened. The construction and contact arrangement for such a push button can be provided, for example, as shown in the application of J. F. Merkel, Ser. No. 158,720, filed August 12, 1937.

An exit button XB is provided for the exit end of each possible route in the track layout, and the exit buttons are located on the track diagram at positions corresponding to the actual exit points in the track layout. Exit buttons 10XB, 11XB, 12XB, 13XB, 14XB, 15XB, 16XB and 17XB are provided for exit points at signals 10, 11, 12, 13, 14, 15, 16 and 17 respectively. The exit buttons XB are of the self-restoring push button type, each having a contact closed only when that button is depressed.

Although separate push buttons have been illustrated for each entrance and exit point associated with each signal, it is to be understood that other forms of control switches could as well be used for those points, and that the entrance and exit buttons for each signal location could as well be combined into a single control switch having distinctive positions to provide the selection of the circuits necessary in accordance with the present invention. It is also to be understood that the distinctive entrance and exit control contacts can be included on one push button with circuit means provided for distinguishing between the entrance and exit operations in a manner such as is shown, for example, in the Preston application, Ser. No. 183,499, filed January 5, 1938.

A switch control lever SML is provided on the control panel for each crossover, as is typically shown in Fig. 2 for governing track switches 4TSA and 4TSB, the lever 4SML having a normal center position, a left hand position for operating the associated track switches to a normal position, and a right hand position for operating the associated track switches to a reverse position. Contacts are provided on the lever for each of those positions.

System devices.—With reference to Figs. 1A, 1B, 1C, 1D, 1E and 1F, each of the entrance buttons NB has associated therewith an entrance repeater relay NR which is picked up in response to the depression of that entrance button, and maintained energized dependent upon the passage of a train, or the actuation of a button for manual restoration to normal.

An exit relay XR is provided for each exit point in the track layout, and that exit relay is

picked up when a route is set up having an exit point with which that relay is associated. Each relay XR is maintained picked up dependent upon the entrance relay NR for the route with which that exit point is associated.

A relay AY or BY is provided for each of the track switches for initially selecting the position of that track switch in accordance with the defining of each entrance point by the depression of an entrance button. Relays 2AY, 3AY and 4AY have been illustrated as being associated with track switches 2TSA, 3TSA and 4TSA respectively, and relays 2BY, 3BY and 4BY have been illustrated as having been associated with track switches 2TSB, 3TSB and 4TSB respectively.

The relays AN, BN and R are provided for causing the operation of the track switches in accordance with routes defined by an operator by the operation of buttons for entrance and exit points. Relays 2AN, 3AN and 4AN are provided for causing the operation of the track switches of crossovers 2ts, 3ts and 4ts to a normal position in accordance with the setting up of routes including that position for the track switches 2TSA, 3TSA and 4TSA respectively. Relays 2BN, 3BN and 4BN are provided for causing the operation of the track switches for the crossovers 2ts, 3ts and 4ts respectively, to a normal position in accordance with the setting up of routes including that position for track switches 2TSB, 3TSB and 4TSB respectively. Relays 2R, 3R and 4R are provided for causing the operation of the track switches for crossovers 2ts, 3ts and 4ts respectively to reverse positions. The relays AN, BN and R are picked up, in accordance with pick-up circuits selected by the Y relays, upon the designation of an exit point during the setting up of a route.

A slow release relay XP is associated with the entrance and exit relays provided for each intermediate signal for the purpose of setting up routes initiated by end-to-end control.

Each of the detector track sections is provided with a normally energized lock relay L as is typically shown in Fig. 2 of the accompanying drawings, relays 8L and 9L having been provided for the detector track sections associated with track switches 4TSA and 4TSB. The control circuits for the relays L have been shown as including contacts of route locking relays ES and WS which are provided for the various track sections in accordance with the requirements of practice. Inasmuch as it is contemplated that such route locking relays ES and WS be controlled as shown in prior applications, the circuits for those relays have not been shown as reference can be made to other applications for the manner in which they are controlled, such as the patent to A. Langdon, Patent No. 2,148,865, dated February 28, 1939. If approach locking is to be used as well as route locking the relays ES and WS can be controlled in a manner similar to that shown for relays bearing similar letter reference characters in the patent to C. F. Stoltz, Patent No. 2,115,511, dated April 26, 1938. It is to be understood that other forms of route and approach locking can as well be used with the entrance-exit system provided by the present invention.

A normally energized lock repeater relay LS is provided for each crossover as is typically shown in Fig. 2 of the accompanying drawings, in which relay 4LS is shown as a repeater of the relays L provided for that crossover.

A polar neutral switch control relay WZ is

provided for controlling the switch machines for each crossover in accordance with the position of the switch control relays AN, BN and R for that particular crossover. Inasmuch as each relay WZ has a similar mode of operation, only the detail circuits for relay 4WZ have been shown, those circuits being typical of the circuits provided for the relays WZ associated with the other crossovers included in the track layout.

Correspondence relays NCR and RCR are provided for each crossover for repeating the position of the track switches in correspondence with the position of the relays AN, BN and R for those track switches. Relays 4NCR and 4RCR have been shown as typical of the correspondence relays provided for each of the crossovers.

A signal control relay G (see Figs. 3A and 3B) is provided for governing each signal, each relay G being energized only when a route has been completely established having that signal as an entrance point.

Having thus considered the apparatus provided in accordance with the present invention, the mode of operation of the system is hereinafter disclosed more in detail in considering various typical operations of the system.

Operation

Normal conditions.—The normal conditions of the system are considered as those conditions which exist when the track sections illustrated are unoccupied, the signals are all at stop, and when there are no entrance or exit points defined by the operation of buttons for those points. An operator is informed of such normal conditions by the various indicator lamps (not shown) which are extinguished under such conditions to provide a "normally dark board" with respect to the illumination of the indicator lamps.

Under normal conditions the track switches are in their last operated positions, which, for illustration of the present disclosure, has been assumed to be the positions providing through routes on each of the parallel tracks.

The lock relays L are normally energized as is typically shown for relays 8L and 9L (see Fig. 2). A circuit is closed for the energization of relay 8L from (+), through a circuit including front contact 24 of relay 8T, front contact 221 of relay 8ES, front contact 222 of relay 8WS, winding of relay 8L, and front contact 25 of relay 8L, to (-). A circuit for maintaining relay 9L picked up under normal conditions is closed from (+), through a circuit including front contact 26 of relay 9T, front contact 223 of relay 9ES, front contact 224 of relay 9WS, winding of relay 9L, and front contact 27 of relay 9L to (-).

With the lock relays L in a picked up position, a circuit is closed, under normal conditions, for each of the lock repeater relays LS, as is typically shown by the circuit for relay 4LS closed from (+), through a circuit including front contact 28 of relay 8L, front contact 29 of relay 9L, back contact 30 of relay 4WZ, and winding of relay 4LS, to (-).

In accordance with the last operated positions of the track switches, as illustrated in Figs. 3A and 3B, the correspondence relay NCR for each of the crossovers is normally energized as is typically shown for relay 4NCR (see Fig. 2). Relay 4NCR is energized under such conditions by a circuit closed from (+), through a circuit including back contact 31 of relay 4R, winding of relay 4NCR, polar contact 32 of relay 4WP in a right hand position, and front contact 33 of relay 4WP, to (-).

Self-selecting network.—It has been heretofore pointed out that the route selector relays AY and BY are so positioned for each track switch included in each route emanating from a designated entrance point, that they select the pick-up circuits for switch control relays in such a manner that, when the picking up of those switch control relays is rendered effective by the actuation of an exit button, the track switches are properly positioned for a route between the designated entrance and exit points.

The control circuits for the route selector relays AY and BY are so provided that those relays are picked up only when the track switches with which they are associated are trailed by traffic in the direction governed by the signal for the designated entrance point. Furthermore, the circuits for each of the route selector relays AY and BY are provided in such a manner that a route selector relay is picked up only if the required position of that track switch to be trailed is to be a particular predetermined position. That is, the circuits for some of the route selector relays provide that they are picked up only if their associated track switches are to be trailed when in normal positions, and the circuit for another route selector relay provides that it is picked up only if that track switch is to be trailed when in a reverse position.

Thus, for example (see Fig. 1C), if an operator designates an entrance point at signal 14 by depressing button 14NB, route selector relay 4BY remains dropped away; but if he designates an entrance point at signal 15 by depressing button 15NB, route selector relay 4BY is picked up.

To consider an example of how a route is set up within an interlocked group, assume an operator, after checking his indicator lamps to find that the proposed route is available, depresses entrance button 14NB. The depression of button 14NB causes the picking up of relay 14NR by closing a circuit from (+), through a circuit including contact 35 of button 14NB closed in a depressed position, front contact 37 of relay 8T, and winding of relay 14NR, to (—). The picking up of relay 14NR closes a stick circuit for maintaining that relay picked up from (+), through a circuit including contact 35 of button 14NB closed in both a depressed and a normal position, front contact 38 of relay 14NR, front contact 37 of relay 8T, and winding of relay 14NR, to (—). In each of the above described circuits, back contact 83 of relay 8TP is connected in the circuit in multiple with front contact 37 of relay 8T to provide that the circuits can be closed again immediately upon entrance of a train into track section 8 if it is desired to set up a route at that time for a following train.

It is to be understood that the back contacts of the track repeater relays TP, connected in multiple with the front contacts of the track relays T in the stick circuits for the entrance relays NR, can be eliminated in conditions encountered in practice where it is not required that an operator be permitted to set up a route for a following train when the preceding train is occupying the track section immediately beyond the entering signal to that route.

To complete the defining of a route having signal 14 as an entrance point, assume an operator to depress the exit button 17XB. Relay 17XR is then picked up when its pick-up circuit is closed from (+), through a circuit including front contact 39 of relay 14NR, back contact 40 of relay 14XR, back contact 41 of relay 4AN, back contact 42 of relay 4BN, back contact 43 of

relay 4BY, winding of relay 17XR, back contact 44 of relay 17NR, and contact 45 of button 17XR closed in a depressed position, to (—). The picking up of relay 17XR closes a stick circuit for that relay extending from (+), through a circuit including front contact 39 of relay 14NR, back contact 40 of relay 14XR, back contact 41 of relay 4AN, back contact 42 of relay 4BN, back contact 43 of relay 4BY, winding of relay 17XR, and front contact 46 of relay 17XR, to (—).

It will be noted from the description of the pick-up circuit for relay 17XR that relays 4AN and 4BN for governing the operation of the track switches for crossover 4ts, must be dropped away before relay 17XR can be picked up, thus providing that relay 17XR can be picked up only when the track switches for crossover 4ts can be operated to a reverse position. In other words, an exit relay XR can be picked up only when a complete route is available between the designated entrance and exit points for the route desired to be set up.

Responsive to the picking up of relay 17XR, relay 4R (see Fig. 1F) is picked up when its circuit is closed from (+), through a circuit including front contact 47 of relay 17XR, back contact 48 of relay 4BY, upper winding of relay 4R, back contact 49 of relay 4BN, and back contact 50 of relay 4AN, to (—). The picking up of relay 4R causes the operation of the track switches 4TSA and 4TSB to a reverse position in a manner hereinafter described when considering further details of the control for the track switches.

To consider another example of how the setting up of routes is accomplished within an interlocked group, assume an operator to set up a route from signal 15 to signal 17 when that route is available, and the system is initially under the normal conditions shown and described.

In response to the depression of button 15NB (see Fig. 1C), relay 15NR is picked up when a circuit is closed of a similar character to that circuit described for the picking up of relay 14NR. Relay 15NR, when picked up, is maintained picked up by a circuit similar to the stick circuit described in detail for relay 14NR.

The picking up of relay 15NR, under such conditions, causes the picking up of relay 4BY when a circuit for that relay is closed from (+), through a circuit including front contact 51 of relay 15NR, back contact 52 of relay 15XR, back contact 53 of relay 4R, and winding of relay 4BY, to (—).

The picking up of relay 4BY allows the picking up of relay 17XR when its circuit is closed upon the depression of the exit button 17XB by an operator, from (+), through a circuit including front contact 51 of relay 15NR, back contact 52 of relay 15XR, back contact 53 of relay 4R, front contact 43 of relay 4BY, winding of relay 17XR, back contact 44 of relay 17NR, and contact 45 of button 17XB closed in a depressed position, to (—). The closing of front contact 46 of relay 17XR provides stick energy for the circuit just described to maintain relay 17XR picked up after button 17XB is restored to normal.

When relay 17XR is picked up, after entrance and exit points have been defined by the operator as being at signals 15 and 17 respectively, a pick-up circuit is closed for relay 4BN (see Fig. 1F) from (+), through a circuit including front contact 47 of relay 17XR, front contact 48 of relay 4BY, upper winding of relay 4BN, and back contact 54 of relay 4R, to (—).

By describing the mode of operation of the

self-selecting network for setting up a route over crossover 4ts requiring its track switches in a reverse position, and by describing the mode of operation in setting up a route requiring track switch 4TSB to be normal, the use of the route selector relay 4BY to select between relays 4R and 4BN has been illustrated; that is, relay 4R is energized when relay 17XR is picked up if relay 4BY is in a dropped away position, and relay 4BN is energized when relay 17XR is picked up if relay 4BY is in a picked up position. Such mode of operation is characteristic of this entrance-exit system, irrespective of the number of track switches included in each route to be set up.

Switch controls.—After considering the mode of operation of the system for setting up routes within an interlocked group, consideration is now given to the means provided for controlling the track switches in accordance with the picking up of the switch control network relays AN, BN and R, and in accordance with the operation of an auxiliary switch control lever SML provided for each crossover. Inasmuch as the track switches for each crossover are controlled in a similar manner, many of the details for the switch control have been shown only for crossover 4ts. It is to be understood that the circuits shown for crossover 4ts are typical of the circuits provided for governing the track switches for each of the other crossovers included in the track layout, and it is also to be understood that similar circuits are provided in practice, as required, for governing single track switches.

With reference to Fig. 2, assume relay 4R to be picked up in setting up a route as heretofore described, for example, from signal 14 to signal 17. The picking up of relay 4R, with relay 8L, 9L and 4LS picked up as described when considering the assumed normal conditions, closes a circuit for the energization of the lower winding of relay 4WZ from (+), through a circuit including front contact 28 of relay 8L, front contact 29 of relay 9L, front contact 55 of relay 5R, and lower winding of relay 4WZ, to (-). The picking up of relay 4WZ, due to such energization, causes the operation of the polar contacts for that relay to a left hand position, and the energization of the switch machine 4SM to operate the associated track switches to a reverse position. Such energization is effected upon the closing of an obvious circuit including front contacts 56 and 57 of relay 4WZ.

The picking up of relay 4R, in setting up the assumed route, causes the dropping away of relay 4NCR by opening its circuit at back contact 31, thus relay 4LS is maintained picked up after relay 4WZ is picked up to open its pick up circuit at back contact 30, by a circuit closed from (+), through a circuit including front contact 28 of relay 8L, front contact 29 of relay 9L, back contact 58 of relay 4RCR, back contact 59 of relay 4NCR, front contact 60 of relay 4LS, and winding of relay 4LS, to (-).

As soon as the track switches 4TSA and 4TSB have been locked in their reverse positions in setting up a route from signal 14 to signal 17, the relay 4WP is picked up when energized with a polarity to operate its polar contacts to a left hand position, and the picking up of that relay closes a circuit for relay 4RCR, from (+), through a circuit including back contact 61 of relay 4AN, back contact 62 of relay 4BN, winding of relay 4RCR, polar contact 32 of relay 4WP in a left hand position, and front contact

33 of relay 4WP, to (-). The picking up of relay 4RCR, due to such energization, causes the dropping away of relay 4LS by opening its stick circuit at back contact 58. The dropping away of relay 4LS closes the signal control circuit for signal 14 as is hereinafter described in considering the detail of the signal control circuits.

When relay 4WP is dropped away as soon as either of the track switches 4TSA and 4TSB have been unlocked from their normal position, a stick circuit is closed from relay 4WZ from (+), through a circuit including back contact 63 of relay 4WP, front contact 64 of relay 4WZ, polar contact 65 of relay 4WZ, in a left hand position, and lower winding of relay 4WZ, to (-). Such stick circuit provides that relay 4WZ is maintained picked up to complete the operation of the switch machine, irrespective of the dropping away of relay 4R, in case an operator cancels the proposed route before the switch machine 4SM has completed its operation.

A similar mode of operation is effected when the track switches are operated from a reverse to a normal position. For example, assume a route to be initiated from signal 15 to signal 17 when the normal conditions of the system exist as described. The picking up of relay 4BN in setting up such a route in a manner heretofore described, causes the picking up of relay 4WZ when a circuit is closed for the upper winding of that relay from (+), through a circuit including front contact 28 of relay 8L, front contact 29 of relay 9L, front contact 67 of relay 4BN, and upper winding of relay 4WZ, to (-). The picking up of relay 4WZ with its polar contacts operated to a right hand position closes an obvious circuit at front contacts 56 and 57 for causing the operation of the switch machine 4SM to a normal position. If the switch machine 4SM is already in a normal position at the time relay 4WZ is picked up, the picking up of relay 4WZ causes the dropping away of relay 4LS to close the signal control circuit by opening its circuit at back contact 30, because the correspondence relay 4NCR remains picked up to hold open the stick circuit for relay 4LS at back contact 59.

If, however, switch machine 4SM is in a reverse position prior to its energization for operation to a normal position, the picking up of relay 4BN opens the above described energized circuit for relay 4RCR to cause that relay to drop away and close back contact 58 in the stick circuit for relay 4LS to cause relay 4LS to be maintained picked up by the stick circuit heretofore described until the track switches 4TSA and 4TSB have been operated to a normal and locked position. The locking of the track switches 4TSA and 4TSB together with the switch machine 4SM in a normal position causes the energization of relay 4WP with its polar contacts operated to a right hand position to cause the picking up of relay 4NCR when its circuit heretofore described is closed. When relay 4NCR is picked up, the stick circuit for relay 4LS is opened at back contact 59 to cause that relay to drop away and close the signal-control circuit.

When relay 4WZ is picked up for operating the switch machine 4SM to a normal position, a stick circuit is closed during the operation of the switch machine to provide that the switch machine will complete its operation, from (+), through a circuit including back contact 63 of relay 4WP, front contact 64 of relay 4WZ, polar

contact 65 of relay 4WZ in a right hand position, and upper winding of relay 4WZ, to (-).

Each of the track switches has an auxiliary control means provided by a switch control lever SML which has a normal center position, a normal operating position shown to the right (see Fig. 2) and a reverse operating position shown to the left.

It is provided that the lock relays L can be picked up only when the auxiliary switch control lever SML for that track switch is in a normal position. Such a mode of operation provides that the track switches can be operated only when the lock relays have had an opportunity to pick up prior to the operation of the switch control lever SML from its normal center position. Thus it is provided that the operation of the lever SML to an operating position causes the operation of the track switches only if those track switches can be positioned at the time the lever is operated. Such a means for preventing the preconditioning of track switches is conveniently called by those familiar with the art "lever lock equivalent."

An example of the pick-up circuits provided for the lock relays for each of the track switches is shown in Fig. 2 in which relay 8L, for example, is picked up only when the detector track section 8 is unoccupied by a train and lever 4SML is in its normal center position. The pick-up circuit is closed under such conditions from (+), through a circuit including front contact 24 of relay 8T, front contact 221 of relay 8ES, front contact 222 of relay 8WS, winding of relay 8L, and contact 68 of lever 4SML in a normal center position, to (-).

When lever 4SML is operated to a right hand normal operating position, at a time when the above described normal conditions of the system exist, relays 4AN and 4BN are picked up when their center windings are energized. The operation of lever 4SML to a normal operating right hand position closes a circuit for relay 4AN from (+), through a circuit including contact 69 of lever 4SML in a right hand position, center winding of relay 4AN, and back contact 70 of relay 4R, to (-). In a similar manner the closing of contact 71 in a right hand position effects the energization of an obvious circuit for relay 4BN. The picking up of relays 4AN and 4BN causes the energization of relay 4WZ and the operation of the switch machine to a normal locked position in the same manner as heretofore described when relay 4BN was assumed to be picked up in setting up a route by operation of the control buttons for the entrance and exit points.

If lever 4SML is operated to a reverse operating left hand position, when the above described normal conditions of the system exist, relay 4R is picked up when its obvious circuit is energized for its center winding upon the closing of contact 69 of lever 4SML in a left hand reverse operating position. The picking up of relay 4R under such conditions of course causes the operation of the switch machine 4SM to a reverse position the same as described when that relay was assumed to be picked up in setting up a route from signal 14 to signal 17.

Signal controls.—When each of the track switches has completed its operation in accordance with the positions required in setting up each proposed route, it has been pointed out that the relay LS associated with that track switch is dropped away to close the signal control circuits.

To consider an example of the signal control circuits provided for each of the signals in the track layout, assume the track switches 4TSA and 4TSB to have completed their operation to a locked reverse position in accordance with a route defined by an operator by the depression of an entrance button for signal 14 and an exit button for signal 17. When relay 4LS has been dropped away, a circuit is closed for relay 14G (see Fig. 3B) from (+), through a circuit including front contact 72 of relay 11XR, back contact 73 of relay 4LS, back contact 74 of relay 4NCR, front contact 75 of relay 4RCR, back contact 76 of relay 4NCR, back contact 77 of relay 4LS, back contact 78 of relay 14XR, front contact 79 of relay 14NR, and winding of relay 14G, to (-). The picking up of relay 14G applies energy at front contacts 80 and 81 to the search light signal mechanism of signal 14 to cause that signal to display a green clear indication.

Route and approach locking.—Inasmuch as the route locking used in this embodiment of the present invention is similar to that typically shown in prior applications, the route locking relays have been shown only in block form in the present disclosure (see Fig. 2). It is to be understood that the circuits by which those route locking relays are controlled are provided as typically shown, for example, in the patent to A. Langdon, Patent No. 2,148,865, dated February 28, 1939. It is also to be understood that other forms of route locking can as well be used, and that, if approach locking is required in practice, the route and approach locking can be provided as shown, for example, in the patent to C. F. Stoltz, Patent No. 2,115,511, dated April 26, 1938.

It is believed, however, that, for an understanding of the present invention, it is sufficient to consider that the relays ES and WS are respectively east and west directional stick normally energized relays, there being an ES relay and a WS relay for each track section of the layout as required. The setting up of any given route causes the ES or WS relay for the proper direction to be deenergized for each track section in such route and to remain dropped away for that portion of such route occupied by, and in advance of, each train, although the entering signal has returned to stop. These relays are then successively energized as the train leaves the track section with which they are respectively associated.

It is obvious, with reference to Fig. 2 of the accompanying drawings, that whenever either of the route locking relays associated with the detector track section for a particular track switch, are dropped away, the lock relay L for that track section is dropped away to cause the electric locking of that track switch to become effective.

Restoration to normal.—To consider how a signal can be restored to stop, and the parts of the system associated with the setting up of routes restored to normal at the will of an operator, assume, for example, an operator to cause the restoration of a route set up as heretofore described from signal 14 to signal 17 by pulling out button 14NB.

When button 14NB is pulled out, the stick circuit for relay 14NR is opened at normally closed contact 35 of button 14NB to cause that relay to drop away. The dropping away of relay 14NR causes the dropping away of signal control relay 14G (see Fig. 3B) by opening the circuit for

that relay at front contact 79, and the opening of front contacts 80 and 81 caused by the dropping away of relay 14G deenergizes the mechanism in signal 14 to cause that signal to be restored to the position to display a red stop indication.

The dropping away of relay 14NR also causes the dropping away of relay 17XR by opening the circuit for that relay at front contact 39. When relay 17XR is dropped away, the upper winding of relay 4R is deenergized, due to the opening of front contact 47 of relay 17XR. Inasmuch as the detector track section is unoccupied at that time, the center winding of relay 4R is deenergized, thus causing that relay to drop away.

A very similar mode of operation is effected upon passage of a train, the principal difference being that the stick circuit for relay 14NR is automatically opened as soon as a train accepts the entering signal 14, instead of being opened by the manual actuation of the entrance button 16NB. To consider an example of such restoration upon passage of a train, assume a route to be set up in a manner which has been described from signal 14 to signal 17, and assume an approaching train to accept signal 14 and enter track section 8.

When a train enters track section 8 and relay 8T is dropped away, under such conditions, the stick circuit for relay 14NR is opened at front contact 37 of relay 8T to cause relay 14NR to drop away and cause the restoration to normal of the relays associated with the route set up including that entrance point, and the restoration of signal 14 to stop, all in the same manner as described above, except that the restoration of relay 4R to normal is delayed until the passing train has left track sections 8 and 9.

Such relay is provided in order to prevent the preconditioning of routes by maintaining an interlock in the self-selecting network. To provide such mode of operation, the center windings of the completion network relays AN, BN and R are energized whenever the track switches with which they are associated are electrically locked either by route, approach, or detector locking.

Thus, relay 4R is maintained picked up under the above assumed conditions as long as the passing train occupies track section 8 because relay 8L is dropped away upon the opening of its circuit at front contact 221 of relay 8ES, and the dropping away of relay 8L closes a stick circuit for relay 4R (see Fig. 2) from (+), through a circuit including back contact 85 of relay 8L, front contact 86 of relay 4R, back contact 87 of relay 4AN, center winding of relay 4R, and back contact 88 of relay 4BN, to (-). When signal 14 is cleared for that route, the dropping away of relay 8ES causes the dropping away of relay 8L by opening its circuit at front contact 223, and the dropping away of relay 8L closes a stick circuit for relay 4R from (+), through a circuit including back contact 89 of relay 9L, front contact 90 of relay 4R, back contact 87 of relay 4AN, center winding of relay 4R, and back contact 88 of relay 4BN, to (-).

As soon as the train leaves the track section 8, relay 8L is picked up, and the stick circuit closed by that relay at back contact 85 is opened, and as soon as the train leaves track section 9, the picking up of relays 9T and 9ES causes the energization of relay 9L which opens the stick circuit for relay 4R at back contact 88. Thus,

relay 4R is maintained energized until both of the detector track sections for its associated track switches are unoccupied, after which it is restored to normal, because the pick-up circuit for that relay is opened by the dropping away of the exit relay 17XR at front contact 47 (see Fig. 1F). It is obvious that the above described circuits for the center winding of relay 4R are effective for either direction of traffic.

Having thus described the mode of operation by which a particular signal can be restored to normal, and the parts of the system associated with the setting up of a particular route restored to normal, it is to be understood that a similar mode of operation is employed for the restoration of each of the other signals included in the track layout, and for the parts of the system associated with the setting up of each of the other routes.

End-to-end control.—To provide that an operator need only actuate the control buttons for the extreme ends of each route to be set up, irrespective of the number of intermediate signals included in that complete route, a system is provided whereby the route initiated is selected by sections in a successive order, a section being provided for each interlocked group, starting with the section for the interlocked group nearest the exit point.

To consider the general mode of operation of the system in setting up routes by end-to-end control, assume, for example, an operator to initiate the setting up of a route from signal 16 to signal 11, at a time when the normal conditions of the system exist as illustrated and heretofore described.

In setting up a route from signal 16 to signal 11, relay 16NR (see Fig. 1F) is picked up when the entrance button 16NB is depressed, and the picking up of relay 16NR applies energy to the initiating network in such a manner as to feed toward the exit relays for all available exit points for routes having an entrance point at signal 16. The picking up of relay 16NR causes the energization of relay 4AY, the picking up of which closes a portion of the selecting network circuit for completing a circuit through to the exit relay for each available exit point. Although the general mode of operation of the system is to pick up a route selector relay Y for each track switch trailed for main line traffic for the particular route set up, the route selector relay 3AY is controlled in a different manner for purposes to be hereinafter pointed out in considering the selection of optional routes. Inasmuch as relay 3AY is not picked up in setting up a route from signal 16 to signal 11, the initiating network circuit for each available exit relay XR can be completed after relay 4AY has picked up. Thus, an operator proceeds to designate the exit point for the proposed route by the depression of button 11XB, and relay 11XR is picked up as a result of such actuation.

When relay 11XR is picked up, in setting up such a route, relay 2R is energized because it is selected in preference to relay 2BN by the dropped away position of the route selector relay 2BY, and the picking up of relay 2R causes the energization of relay 3AN in preference to relay 3R because the route selector relay 3AY is dropped away. After relay 3AN is picked up, relay 12XP is energized, and the picking up of that relay effects the energization in turn of relays 12NR and 14XR respectively. Upon the picking up of relay 14XR, relay 12XP is deenergized and al-

lowed to drop away, after completing its principal purpose of causing the picking up of the entrance relay associated with signal 12, and after causing the picking up of the next exit relay 14XR. When relay 14XR is picked up, relay 4AN is energized in preference to relay 4R because the route selector relay 4AY is already picked up to select that particular relay.

Thus, the switch control relays in the completion network are positioned for the entire route designated, and the track switches with which those relays are associated are positioned in a manner similar to that which has been heretofore described as typical for the track switches associated with crossover 4ts. After the track switches have completed their operation to positions required for such a route, the signals for each of the interlocked groups provided for governing traffic through that route are cleared, each signal being energized by circuits provided for that particular interlocked group in a manner which has been heretofore described as typical of all signal control circuits.

Having thus considered the general mode of operation in setting up a route by end-to-end control, consideration will now be given to the details of the circuits which provide such mode of operation, it being assumed that the normal conditions of the system exist as heretofore described, and that an operator proceeds to set up a route as heretofore described in a general manner from signal 16 to signal 11.

The actuation of button 16NB in setting up such a route, causes the picking up of relay 16NR (see Fig. 1F) by the energization of a circuit closed from (+), through a circuit including contact 91 of button 16NB closed in a depressed position, front contact 92 of relay 8T, and winding of relay 16NR, to (-). The picking up of relay 16NR closes a stick circuit for that relay from (+), through a circuit including contact 91 of button 16NB closed when button 16NB is both normal and depressed, front contact 93 of relay 16NR, front contact 92 of relay 8T, and winding of relay 16NR, to (-). Back contact 215 of relay 8TP is connected in multiple with front contact 92 of relay 8T to provide that relay 16NR can be picked up when track section 8 is occupied as well as when it is unoccupied.

Upon the picking up of relay 16NR a circuit is closed to cause the picking up of relay 4AY by the energization of a circuit closed from (+), through a circuit including front contact 94 of relay 16NR, back contact 95 of relay 16XR, back contact 96 of relay 4R, and winding of relay 4AY, to (-).

When an operator designates the exit point for the route being set up, by the depression of button 11XB, a circuit is closed for relay 11XR, from (+), through a circuit including front contact 94 of relay 16NR, back contact 95 of relay 16XR, back contact 96 of relay 4R, front contact 97 of relay 4AY, back contact 98 of relay 14XR, wire 102, back contact 104 of relay 12NR, back contact 105 of relay 12XR, back contact 106 of relay 3R, back contact 107 of relay 3AY, wire 108, back contact 109 of relay 2BN, back contact 110 of relay 2AN, back contact 111 of relay 2BY, winding of relay 11XR, back contact 112 of relay 11NR, and contact 113 of button 11XB closed in a depressed position, to (-). Upon the picking up of relay 11XR, a stick circuit is closed for that relay at front contact 114 to shunt out, in the circuit above described, contacts 112 of relay 11NR and 113 of button 11XB.

Upon the picking up of relay 11XR, relay 2R is picked up when its circuit is energized from (+), through a circuit including front contact 115 of relay 11XR, back contact 116 of relay 2BY, lower winding of relay 2R, back contact 117 of relay 2BN, and back contact 118 of relay 2AN, to (-). When relay 2R is picked up, a circuit is closed to cause the picking up of relay 3AN, from (+), through a circuit including front contact 115 of relay 11XR, back contact 116 of relay 2BY, front contact 119 of relay 2R, wire 120, back contact 121 of relay 3AY, lower winding of relay 3AN, and back contact 122 of relay 3R, to (-).

A circuit is closed upon the picking up of relay 3AN for the energization of relay 12XP, from (+), through a circuit including front contact 115 of relay 11XR (see Fig. 1D), back contact 116 of relay 2BY, front contact 119 of relay 2R, wire 120, back contact 121 of relay 2AY, front contact 123 of relay 3AN, winding of relay 12XP, and back contact 124 of relay 12NR, to (-). When relay 12XP is picked up, a stick circuit is closed for that relay to shunt back contact 124 of relay 12XR out of the circuit just described by a circuit closed from wire 125, through a circuit including front contact 126 of relay 12XP, wire 127, and back contact 128 of relay 14XR, to (-).

A circuit is closed upon the picking up of relay 12XP for relay 12NR, from (+), through a circuit including normally closed contact 129 of button 12NB, front contact 130 of relay 12XP, front contact 134 of relay 6T, and winding of relay 12NR, to (-). A stick circuit is closed for relay 12NR upon the picking up of that relay from (+), through a circuit including normally closed contact 129 of button 12NB, front contact 135 of relay 12NR, front contact 134 of relay 6T, and winding of relay 12NR, to (-).

Back contact 216 of relay 6TP is connected in multiple with front contact 134 of relay 6T to provide that relay 12NR can be picked up when track section 8 is occupied as well as when it is unoccupied.

The initiating circuit by which relay 11XR is maintained energized, is maintained closed during the shifting of contact 104 of relay 12NR by front contact 217 of relay 12XP connected in multiple with back contact 104. The picking up of relay 12NR applies energy to the initiating network for energization of relay 11XR at front contact 104 the same as is done in setting up a route within that interlocked group.

Upon the picking of relay 12NR, a circuit is closed for relay 14XR from (+), through a circuit including front contact 94 of relay 16NR (see Fig. 1F), back contact 95 of relay 16XR, back contact 96 of relay 4R, front contact 97 of relay 4AY, winding of relay 14XR, back contact 136 of relay 14NR, wire 137, front contact 139 of relay 12NR, and front contact 140 of relay 12XP, to (-). The picking up of relay 14XR, due to such energization, closes a stick circuit for that relay from (+), through a circuit including front contact 94 of relay 16NR (see Fig. 1F), back contact 95 of relay 16XR, back contact 96 of relay 4R, front contact 97 of relay 4AY, winding of relay 14XR, and front contact 141 of relay 14XR, to (-).

The picking up of relay 14XR causes the dropping away of relay 12XP by opening the stick circuit for that relay at back contact 128 (see Fig. 1F), the pick-up circuit for that relay having been opened upon the picking up of relay 12NR at back contact 124 (see Fig. 1E).

When relay 14XR is picked up in setting up a

route from signal 16 to signal 11, relay 4AN is picked up by the energization of a circuit closed from (+), through a circuit including front contact 142 of relay 14XR (see Fig. 1F), front contact 143 of relay 4AY, lower winding of relay 4AN, and back contact 54 of relay 4R, to (-).

Thus, the circuits have been completely described by which the self-selecting network is positioned in setting up a route by end-to-end control, and it is believed that it can be readily understood by those familiar with the art how the track switches are positioned and the signals are cleared for the route being set up in a manner which has been heretofore typically illustrated and described.

When the end-to-end system described above as typical, it will be readily apparent to those familiar with the art how the system can be applied to any particular track layout in accordance with the requirements of practice, and how the end-to-end system of control can be extended through as many interlocked groups as desired.

It may be well at this time to give some consideration to the reasons for certain of the circuit selections, and the affects of those selections on the mode of operation of the system.

It is provided that the parts of the system associated with end-to-end control are used only while the route is being set up. That is, after each complete route is set up, the condition of the system is the same as if that route had been set up by sections from signal to signal through each interlocked group. Thus, the restoration to normal of the system associated with a route set up by end-to-end control is effected for each in the locked group included in the route, the same as heretofore described for a particular route within an interlocked group.

Although a through route may be set up through several interlocked groups by merely entrance and exit manipulations for the ends of such through route, it must be restored by individually pulling the buttons NB at the entrance to each of the groups included in the through route.

Preferred route selection.—It has been heretofore pointed out in a general manner what conditions are encountered in practice in connection with the selection of a preferred route of a plurality of optional routes, and the means provided by the self-selecting network for selecting a particular preferred route. A means has been pointed out in the above mentioned prior Langdon application Ser. No. 119,641, filed January 8, 1937, and Patent No. 2,148,865, dated February 28, 1939, whereby, of several optional routes available, the route diverging nearest the entrance point is always given preference. Consideration is now given more in detail to the means provided by this invention whereby any particular route can be given preference over a plurality of optional routes available, irrespective of whether or not it diverges nearest the entrance or exit point.

Thus, it has been provided in the present embodiment of this invention that a route set up from signal 17 to signal 10 is set up via crossover 3ts in preference to the inferior optional route via crossover 4ts. Such preference is accomplished by the control circuit for the route selector relay 3AY (see Fig. 1E) associated with track switch 3TSA.

To consider the general mode of operation of the system by which the route from signal 17 to

signal 10 via crossover 3ts is made preferred, the initiating network circuits can be considered to assume a form similar in effect to the actual track layout for which the system is provided. That is, the network system feeds energy, when an entrance point is designated, for example, at signal 17, at a time when the heretofore described normal conditions of the system exist, through the initiating network circuits toward the exit relay for each available exit point. Thus, energy can be said to feed in directions corresponding to traffic through the actual track layout in the field from entrance relay 17NR through a normal branch of the network circuits associated with crossover 4ts to relay 15XR, and through a branch of the network corresponding with the crossover 3ts having its track switches 3TSA and 3TSB in a reverse position to exit relay 10XR. There is also a multiple path, as there is in the track layout from relay 17NB through a branch of the initiating network corresponding to crossover 4ts with its track switches 4TSA and 4TSB in reverse positions to exit relay 14XB, and through a branch of the self-selecting network corresponding with the normal position of the track switches associated with crossover 3ts to exit relay 10XB.

The route selector relays Y, as has been heretofore pointed out, are connected in multiple in the initiating network at various points where selections are included for the track switches with which those relays are associated. Thus, a relay 4AY (see Fig. 1F) is provided in the initiating network in the normal branch of the network extending from a front contact of relay 16NB; and when relay 4AY is dropped away, the reverse branch of the self-selecting network is closed from a front contact of entrance relay 17NB over the reverse branch of the initiating network circuits corresponding with crossover 4ts with its track switches in the reverse position, and when relay 4AY is picked up, that reverse branch of the circuit is opened, and the normal branch of the circuit extending from a front contact of entrance relay 16NB, to exit relay 14XB, is closed.

The relay 3AY (see Fig. 1E), associated with track switch 3TSA, however, is energized from the branch of the initiating network corresponding with crossover 3ts having its track switches in a reverse position. When relay 3AY is dropped away, the circuits through the self-selecting network are closed through the normal branch corresponding with the track including track switch 3TSA in a normal position, and when that relay is picked up, the initiating network circuits for setting up routes for west bound traffic are closed through a branch of the circuit corresponding to crossover 3ts having its track switches in reverse positions. It is thus provided that, in setting up a route from signal 17 to signal 10, the branch of the initiating circuit network is closed corresponding to the route between those designated entrance and exit points via crossover 3ts because relay 3AY becomes energized, and the branch of the initiating network corresponding to the route designated between signal 17 and signal 10 via crossover 4ts is opened upon the picking up of relay 3AY.

Such mode of operation renders the portion of the self-selecting network corresponding with the route diverging nearest the entrance point ineffective for setting up such a route, and gives preference to the particular route for which the

route selector relay Y is energized in the reverse branch of the initiating network control.

To consider details of the mode of operation by which the route from signal 17 to signal 10 via crossover 3ts is given preference over other routes, assume an operator to depress button 17NB at a time when the normal conditions of the system exist as heretofore described. As a result of such actuation relay 17NR (see Fig. 1F) is energized by circuits closed in a manner similar to that described associated with the circuits for relay 16NR as typical, and the picking up of relay 17NR provides energy for relay 3AY by a circuit closed from (+), through a circuit including front contact 144 of relay 17NR, back contact 145 of relay 17XR, back contact 146 of relay 4R, back contact 147 of relay 15XR, wire 149, back contact 151 of relay 13NR, back contact 152 of relay 13XR, back contact 153 of relay 3BN, back contact 154 of relay 3AN, and winding of relay 3AY, to (-). The picking up of relay 3AY opens the normal branch of the initiating network circuit at back contact 107.

Upon designation of the exit point for the route being set up, by the depression of button 10XB, an operator causes the picking up of relay 10XR, (see Fig. 1D) by the energization of a circuit closed from (+), through a circuit including front contact 144 of relay 17NR (see Fig. 1F), back contact 145 of relay 17XR, back contact 146 of relay 4R, back contact 147 of relay 15XR, wire 149, back contact 151 of relay 13NR, back contact 152 of relay 13XR, back contact 153 of relay 3BN, back contact 154 of relay 3AN, front contact 107 of relay 3AY, wire 108, back contact 155 of relay 2R, winding of relay 10XR, back contact 156 of relay 10NR, and contact 157 of button 10XB closed in a depressed position, to (-). The picking up of relay 10XR closes a circuit at front contact 158 to shunt contacts 157 and 156 out of the circuit heretofore described.

Upon the picking up of relay 10XR, a circuit is closed for the energization of relay 2AN, from (+), through a circuit including front contact 159 of relay 10XR, lower winding of relay 2AN, and back contact 160 of relay 2R, to (-). When relay 2AN is picked up, a circuit is closed to cause the picking up of relay 3R from (+), through a circuit including front contact 159 of relay 10XR (see Fig. 1D), front contact 161 of relay 2AN, wire 120, front contact 121 of relay 3AY, lower winding of relay 3R, back contact 162 of relay 3BN, and back contact 163 of relay 3AN, to (-). When relay 3R is picked up, a circuit is closed for the energization of relay 13XP from (+), through a circuit including front contact 159 of relay 10XR (see Fig. 1D), front contact 161 of relay 2AN, wire 120, front contact 121 of relay 3AY, front contact 164 of relay 3R, winding of relay 13XP, and back contact 165 of relay 13NR, to (-). Upon the picking up of that relay a stick circuit is closed to maintain that relay energized until relay 15XR is picked up, from (+), through a circuit including front contact 159 of relay 10XR, front contact 161 of relay 2AN, wire 120, front contact 121 of relay 3AY, front contact 164 of relay 3R, winding of relay 13XP, front contact 166 of relay 13XP, wire 167, and back contact 168 of relay 15XR, to (-).

A circuit is closed for the energization of relay 13NR (see Fig. 1E), upon the picking up of relay 13XP, from (+), through a circuit including contact 169 of button 13NB closed in a normal position, front contact 170 of relay 13XP, front contact 174 of relay 7T, and winding of relay 13NR, 75

to (-). When relay 13NR is picked up, a stick circuit is closed for that relay the same as just described except that front contact 175 of relay 13NR is closed to shunt front contact 170 of relay 13XP out of the circuit.

The initiating circuit by which relay 10XR is maintained energized, is maintained closed during the shifting of contact 151 of relay 13NR (see Fig. 1D) by front contact 218 of relay 13XP connected in multiple with contact 151. The picking up of relay 13NR applies energy to the initiating network for energizing relay 10XR at front contact 151 the same as is done in setting up a route within an interlocked group.

After relay 13NR is picked up, a circuit is closed for the energization of relay 15XR, from (+), through a circuit including front contact 144 of relay 17NR (see Fig. 1F), back contact 145 of relay 17XR, back contact 146 of relay 4R, 20 winding of relay 15XR, back contact 175 of relay 15NR, wire 176, front contact 178 of relay 13NR, and front contact 179 of relay 13XP, to (-). When relay 15XR is picked up, the above described stick circuit for relay 13XP is opened at back contact 168 to cause relay 13XP to drop away.

A stick circuit is closed, upon the picking up of relay 15XR at front contact 219 of relay 15XR, from (-), through a circuit including front contact 144 of relay 17NR, back contact 145 of relay 17XR, back contact 146 of relay 4R, winding of relay 15XR, and front contact 219 of relay 15XR, to (-).

Upon the picking up of relay 15XR, under such conditions, relay 4BN is picked up by the energization of a circuit closed from (+), through a circuit including front contact 180 of relay 15XR, lower winding of relay 4BN, and back contact 54 of relay 4R, to (-).

40 Responsive to the picking up of relays 2AN and 4BN, the track switches associated with crossovers 2ts and 4ts are operated to their normal positions, and responsive to the picking up of relay 3R, the track switches associated with crossover 3ts are operated to their reverse positions, all in a manner similar to the condition described as typical of the system when considering the details of the switch control circuits.

After the track switches have assumed their selected positions, the signals are cleared as a result of the energization of circuits similar to a signal control circuit heretofore described as typical of the circuits provided for clearing each of the signals.

55 It is therefore readily apparent that, in order to give a route via a particular track switch preference over optional routes, irrespective of the location of the track switches in the route, the Y relay energized for that particular track switch or crossover for that particular direction of traffic is energized in the reverse control branch of the initiating network, and the reverse switch control relay for controlling that track switch is selected for energization when the Y relay is picked up.

In view of the nature of the means provided for causing a particular route to be preferred, the same system can be used in causing a particular route to be preferred over optional routes within an interlocked group. Thus, for example, in setting up a route from signal 11 to signal 13, it is necessary to select between the two optional routes, one of which includes the track switches associated with crossovers 2ts and 3ts in normal positions, and the other of which includes the

track switches of crossovers 2ts and 3ts in reverse positions. In accordance with the present embodiment of the invention, it has been provided that the preferred route between those entrance and exit points is the route with the track switches in their normal positions. Such preference is provided by causing the route selector relay (see Fig. 1B) 3BY to be energized in the normal branch of the self-selecting network associated with crossover 3ts. However, if it were desirable to provide that the preferred route between signal 11 and signal 15 were to be via crossovers 2ts and 3ts with their track switches in reverse positions, relay 3BY would be energized from the reverse branch of the initiating network associated with crossover 3ts in a manner similar to that heretofore described in detail when considering the energization of relay 3AY provided for setting up routes for west bound traffic.

With this thought in mind, it is readily apparent that the relay 4BY (see Fig. 1C) associated with setting up routes for east bound traffic is necessarily energized from the normal branch of the initiating network rather than the reverse branch, in order to provide that, in setting up a route between signal 11 and signal 17, the through route on the lower track is given preference over the run-around route including crossovers 2ts and 4ts.

Having described the present invention as applied to a particular problem encountered in practice, it is desired to be understood that the invention is not limited to the specific form shown, and that additions, modifications, and changes can be made to adapt the system provided by the present invention to various requirements of practice, without in any manner departing from the spirit or scope of the present invention, except as limited by the scope of the following claims.

What I claim is:

1. In a switch and signal control system of the character described; a track layout having a plurality of track switches for setting up optional routes extending between an entrance point and an exit point; manually operable contact means for the entrance and exit points; a preselecting relay for each track switch trailed in each of the optional routes; circuit means responsive to the actuation of the manually operable contact means associated with the entrance point for energizing said preselecting relay whenever a route is available between the entrance and exit points over its track switch in a reverse position; and route establishing means rendered effective upon the actuation of said manually operable contact means for the exit point following the operation of said manually operable contact means for the entrance point and controlled by said preselecting relay so as to set up that particular optional route diverging nearest the exit point including its track switch in a reverse position if such preselecting relay is energized but to set up another of said optional routes if such preselecting relay is deenergized.

2. In a switch and signal control system of the entrance-exit type for governing train movements through a track layout having a plurality of optional routes extending between an entrance and an exit point; route selecting means for a track switch in a trailing relation to the entrance point and acting when energized to pre-select said switch for operation to the reverse

position in preference to the normal position; manually operable contact means for each of the entrance and exit points; circuit means for energizing said route selecting means, upon actuation of said contact means for the entrance point, when and only when, a route is available over said track switch in a reverse position between such points, and route establishing means responsive to the joint actuation of said contact means for the entrance and exit points, for setting up one or the other of said optional routes in accordance with the condition of said route selecting means, whereby each of said optional routes may be established in a preferred order, only one route being set up at any one time, and preference being given the route including said given track switch in a reverse position whenever that route is available for use.

3. In a switch and signal control system of the character described; a track layout including crossovers providing two optional routes extending between common entrance and exit points; route selecting means for the crossover nearest the exit point, which, when energized, selects a reverse position for the track switches of that crossover, and when deenergized selects a normal position for those track switches; manually operable contact means associated with the entrance and exit points; circuit means responsive to the actuation of the contact means associated with the entrance point for energizing said route selecting means when and only when a route is available from that entrance point over the crossover nearest said exit point, and route establishing means rendered effective upon the actuation of said contact means for the exit point, following the actuation of said contact means for the entrance point, for setting up a route between said entrance and exit points via the crossover nearest said exit point if said route selecting means is energized, and via the crossover nearest said entrance point if said route selecting means is deenergized.

4. In a switch and signal control system of the character described, a track layout having track switches forming a plurality of optional routes extending between a single entrance point and a single exit point, manually operable contact means for said entrance and exit points, a pre-selecting relay for a particular one of the track switches included in the optional routes facing said exit point, circuit means responsive to the actuation of the manually operable contact means for said entrance point for energizing said preselecting relay, means for rendering said circuit means ineffective when said particular switch in its normal position is included in any established or occupied route, and route establishing means rendered effective upon the joint actuation of said contact means for the entrance point and the entrance point to establish one of said optional routes between such points, said route establishing means being controlled by said preselecting relay so that a particular optional route which includes said particular track switch in a reverse position is selected when said preselecting relay is energized, and another optional route which includes said particular track switch in a normal position is selected when said preselecting relay is deenergized.

5. In a switch and signal control system of the character described; a track layout having a plurality of routes extending between entrance and exit points, said different routes including at least two optional routes between a common en-

trance point and a common exit point; manually operable contact means for each of said entrance and exit points; a preselecting relay, a normal control relay and a reverse control relay for each track switch or end of a crossover; an initiating circuit network conforming to said track layout and including back contacts of said normal and reverse control relays and certain of said preselecting relays, said preselecting relays being included in those portions of an initiating circuit network corresponding to the normal trailing point positions of the track switches except in the case of said optional routes where the preselecting relay for a particular one of the track switches is included in the reverse trailing position; means effective upon the actuation of any given entrance contact means for applying energy to said initiating circuit network at a corresponding point, whereby a preselecting relay for each of the track switches trailed normal in available routes emanating from that point is energized except in the case of the preselecting relay for said particular track which is energized when it is trailed reverse in one of such available routes; and completion circuit means rendered effective upon the subsequent actuation of any given contact means for an exit point for energizing the normal and reverse relays in accordance with the positions of said preselecting relays between the entrance and exit points associated with the operated contact means for such points and as required to set up the superior available route between such points, the preselecting relay for said particular track switch causing the completion circuit network to establish that particular optional route including such particular track switch in the reverse position in preference to the other of said two optional routes if such preselecting relay is energized.

6. In a switch and signal control system; two parallel sections of main track, each extending between two signal locations, said sections of track being interconnected by two crossovers to provide two alternative routes between the two opposing signals for the two different parallel sections of track; manually operable contact means for the entrance points corresponding to said signal locations; manually operable contact means for the exit ends of the routes governed by said signals; a preselecting relay for a given trailing position for each of said track switches; initiating circuit means responsive to the actuation of the manually operable contact means for a given entrance point for energizing the preselecting relay for each track switch trailable in any route emanating from such entrance point for that position of that track switch for which its preselecting relay is provided, said preselecting relays being provided for the normal trailing positions of their switches except for that one of said track switches which must be in different positions for said alternative routes; and route establishing means controlled by the joint operation of the manually operable contact means for an entrance point and the manually operable contact means for an exit point so as to establish a route between such points dependent upon the energized or deenergized conditions of said preselecting relays for the switches in that route facing the exit end of such route, said route establishing means operating each such track switch in that route to the position for which its preselecting relay is provided if such preselecting relay is energized

and to operate such track switch to the opposite position if its preselecting relay is deenergized, and operating the remaining track switches as required to establish that route, said route establishing means also effecting the clearing of the signal at the entrance end of the route thus established.

7. In a switch and signal control system of the character described for a track layout including a plurality of interlocked groups adjoining end-to-end, there being track switches in each group for setting up different routes and a signal for governing traffic at each point of entrance to each of the groups in both directions, the location of such signals constituting entrance and exit points for the various routes; manually operable contact means for each of the entrance and exit points; an entrance relay for each of said entrance points; circuit means controlled by each of said manually operable contact means for said entrance points for picking up its associated entrance relay; stick circuit means for each of said entrance relays automatically deenergized upon the passage of a train past its associated signal location and also being manually deenergizable; route establishing means for each of said interlocked groups controlled by the picking up of any given entrance relay for that group in response to the actuation of said manually operable contact means for its entrance point and controlled by the actuation of the manually operable contact means for any given exit point for setting up a route between such entrance and exit points and clearing a signal at the entrance point having its entrance relay picked up; through route interconnecting means for interconnecting the route establishing means for adjacent interlocked groups so as to cause the response of a given route establishing means upon the actuation of the manually operable contact means for an exit point of its interlocked group following the picking up of an entrance relay for some preceding interlocked group the same as if an entrance relay for its interlocked group had been picked up but failing to clear an entering signal for its group until such corresponding entrance relay is picked up; automatic circuit means rendered effective upon the setting up of a route in said given interlocked group by its route establishing means for automatically picking up the entrance relay at the entering end of that route for such interlocked group; and circuit means momentarily effective upon the picking up of an entrance relay by said automatic circuit means for initiating operation of the route establishing means for the preceding interlocked group the same as if a manually operable contact means had been operated for the adjacent exit point, said circuit means also being effective to open said through route interconnecting means for such adjoining point of the two adjacent interlocked groups.
8. In a switch and signal control system of the character described for governing traffic in a particular direction through a track layout consisting of a first and second track portion adjoining respectively end-to-end to form a composite through route between extreme entrance and exit points, each of such track portions providing in itself a route between an entrance and an exit point; manually operable contact means for each entrance and exit point; an entrance relay for each entrance point; circuit means responsive to the actuation of the contact

means for each of the entrance points for energizing the entrance relay for that point; circuit means for maintaining each of said entrance relays energized, dependent for deenergization upon passage of a train past that entrance point; route establishing means for each of the track portions responsive to the combined energization of the entrance relay for that portion and the actuation of the contact means for the exit point for that portion for setting up a route between those designated entrance and exit points, the route establishing means for the second track portion being also responsive to the combined energization of the entrance relay for the first track portion and the actuation of the contact means for the exit point of the second track portion; circuit means rendered effective upon setting up of a route through the second track portion as a result of the combined energization of the entrance relay for the first track portion and the actuation of the contact means for the exit point for the second track portion, for temporarily energizing said entrance relay for the second track portion and initiating operation of the route establishing means for the first track portion the same as if the contact means for the exit point of that portion had been actuated in combination with the picking up of the entrance relay for that portion; and circuit means for maintaining said route establishing means for each portion energized dependent upon the energization of the entrance relay for that portion, whereby a through route is set up by actuation of the contact means for the extreme ends of that route, and the route establishing means for each portion is automatically restored to normal upon the passage of a train through that portion.

9. In a switch and signal control system of the entrance-exit type for a track layout including a plurality of interlocked groups adjoining end-to-end, there being entrance and exit points to each interlocked group; manually operable contact means for each entrance point and for each exit point to each route within each interlocked group; route establishing means responsive to the actuation of said contact means for each entrance and each exit point to each interlocked group for setting up an available route extending between the entrance and exit points thus designated, said route establishing means also being responsive to the actuation of said contact means for an entrance point to one interlocked group together with the actuation of said contact means for an exit point to a subsequent interlocked group for setting up a route between the entrance and exit points thus designated, such through route being established over the interlocked groups, one group at a time in turn, starting with said subsequent group; an entrance stick relay acting while energized to maintain said route establishing means for each interlocked group effective for each group set up; means for energizing each entrance relay by actuation of the corresponding manually operable contact means or by establishing a route originating at the corresponding signal location by through route control; and means for deenergizing each entrance relay by manual control or automatically by the movement of a train past the corresponding signal.

10. In a switch and signal control system for governing the power operation of track switches and the clearing of signals in setting up routes and governing traffic between entrance and exit points in a track layout providing a plurality

of conflicting routes and a plurality of interlocked groups connected end-to-end, manually operable contact means for each entrance and exit point, an entrance relay for each entrance point, an exit relay for each exit point, circuit means for energizing each of said entrance relays when the contact means for that entrance point is actuated or when that entrance point is included as an intermediate point in a through route set up, circuit means for maintaining each entrance relay energized dependent for deenergization upon the passage of a train past that entrance point, an initiating circuit network effective to condition each of said exit relays included in a possible route available emanating from a designated entrance point so that such exit relay can be picked up upon the selection of a route up to that point from the exit point designated, or upon actuation of said contact means associated with that exit point, route establishing means responsive to the picking up of each exit relay for setting up a route within that interlocked group between the entrance and exit points designated, and circuit means for maintaining said route establishing means energized dependent for deenergization upon the dropping away of the entrance relay for the portion of the route set up extending through that interlocked group.

11. A switch and signal control system for governing the power operation of track switches and the clearing of signals for railway track layouts including a plurality of interlocked groups and affording one or more through routes past one or more intermediate signals comprising, manually operable buttons for designating entrance and exit ends of routes afforded by the track layout, an entrance stick relay for each entrance signal, circuit means responsive to the actuation of a button to designate an entrance signal location for energizing the corresponding entrance stick relay, track circuit controlled means for maintaining each entrance stick relay energized until a train passes the corresponding signal, a signal clearing circuit for each signal controlled by the corresponding entrance relay, an exit stick relay for each signal location constituting the exit ends of routes, initiating circuits responsive to the energization of any given entrance relay for conditioning switches in one or more interlocked groups for operation to positions to conform with any one of the available routes or through routes originating at said entrance signal location; said initiating circuits also preparing energizing circuits for the exit relays for the exit ends of said available route so that each of said exit relays may be energized by actuation of a corresponding control button, route completion means associated with each interlocked group and responding to the energization of an exit relay thereof for operating switches in that interlocked group in accordance with the conditioning of said switches by said initiating circuits and thereby set up a route connecting with a particular entrance signal of that interlocked group, and means associated with each intermediate signal in a through route and responding to such operation of said route completion means in setting up a route connecting with said intermediate signal for causing energization of the entrance relay for said intermediate signal and the exit relay of a route in the next adjoining interlocked group terminating at said intermediate signal, whereby routes in successive interlocked groups and constituting

parts of an available through route are established in turn and the entrance relay for each intermediate signal in said route is energized by the manual actuation of control buttons to designate the extreme entrance and exit ends of said through route.

12. In an interlocking control system, a plurality of traffic routes through a track layout, route buttons for the ends of the routes, a preliminary and a final selector for said routes each including relays, said final selector having a relay for each switch, an entrance stick relay responsive to the momentary operation of the button marking one end of a particular route for energizing the preliminary selector relay for each route having the same one end, means responsive to the subsequent operation of the button for the other end of said particular route for energizing the final selector relays for said particular route only, means controlled by the energized final selector relays for establishing said particular route and for releasing the energized relay for any routes conflicting therewith, and means for automatically releasing said entrance relay for said established route when a train enters the first track section of said route.

13. In a switch and signal control system, a track layout including parallel tracks interconnected by track switches to form different traffic routes, manually operable buttons for closing contacts to designate signal locations as the entrance or exit end of desired routes, a preliminary selector including relays and initiating circuits for energizing said relays, an entrance stick relay for an entrance signal location responsive to the momentary closing of the corresponding entrance contact by actuation of its associated button for energizing the preliminary selector relay relating to all available routes originating at said entrance signal location, means controlled by the preliminary selector relays thus energized for preventing energization of the initiating circuits for any conflicting route converging upon any one of said available routes in one direction, a chain of final selector relays for each route and including a relay for each switch in the route, means responsive to the momentary closing of a manually operable exit contact for one of said available routes for energizing in succession the final selector relays for each switch in that route and for releasing the energized preliminary selector relay for any other route, means controlled by the energization of said final selector relays for said selected route for preventing energization of similar relays for any conflicting route converging upon said selected route in the other direction, switch control relays for said switches energized in response to the energization of said final selector relays, and means for automatically releasing said energized entrance relay when a train passes the corresponding signal.

14. In combination, a track layout comprising a plurality of track sections interconnected by track switches to form different traffic routes, route buttons for the ends of the routes, a selector for each route, means responsive to the momentary operation of a button for energizing the selector for each route having its entrance end marked by such button, means responsive to the subsequent momentary operation of the button for the other end of a selected one of said routes for releasing all said selectors except the one for the selected route and for operating the track switches as required to establish

that route, and means for automatically releasing said one selector when a train enters the first track section of the route.

15. In an interlocking control system, a track layout comprising a plurality of track sections interconnected by track switches to form different routes, route buttons for the ends of the routes, a preliminary and a final selector for each route, means responsive to the momentary operation of the button marking the entrance end of diverging routes for energizing the preliminary selector for each such route, means controlled by the track relay for the track section at said entrance end for maintaining said selectors energized, means responsive to the subsequent momentary operation of the button for the exit end of a selected one of said routes for energizing the final selector for the selected route, means controlled by said final selector for releasing all said preliminary selectors except the one for the selected route, means controlled by the preliminary selector for the selected route for maintaining said final selector energized, and means controlled by said final selector for operating the track switches as required to establish the selected route.

16. In an interlocking control system, a track layout including track switches arranged to form different routes for governing traffic in two directions, an entrance relay and an exit relay for each route end, manually operable means for successively energizing the entrance and exit relays for the opposite ends of a selected route, a route selecting circuit for each route for the corresponding direction, means controlled by each entrance relay when energized for preparing the selecting circuit for each route having the corresponding entrance point, means responsive to the energization of an exit relay for the exit end of a route having its selecting circuit prepared for maintaining such exit relay energized over said prepared circuit under the control of the energized entrance relay, normal and reverse route relays for governing the operation of the track switches to their normal and reverse positions, a route circuit network including a route circuit for each route, means controlled by each entrance relay when energized for preparing the route circuit for each route having the corresponding entrance point, means controlled by each exit relay when energized for energizing the prepared route circuit for the route having the corresponding exit point to energize the route relays as required to establish said route, and means governed by the energized route relays for isolating the selecting circuit and the route circuit for the selected route from the circuits for conflicting routes.

17. In an interlocking control system, a track layout including track switches arranged to form different routes for governing traffic in two directions, manually operable means for each route end, an entrance relay and an exit relay for each route end, means controlled by each manually operable means for energizing the associated entrance relay, a route selecting circuit network for each direction comprising a route circuit for each route including a front contact of the entrance relay for one end and the winding of the exit relay for the other end of such route each said network including selecting relays energized in response to the energization of the entrance relays for the entrance ends of certain ones of said routes said selecting relays being effective to isolate the corresponding se-

lecting circuits from those for converging routes, normal and reverse route relays for governing the operation of the track switches to their normal and reverse positions, a route circuit network comprising a route circuit for each route selected in response to the operation of said selecting relays for controlling said route relays, means responsive to the operation of the manually operable means for the exit end of a route having its selecting circuit energized for energizing the associated exit relay, means controlled by the exit relay for a selected route when energized for connecting a source of current to the corresponding end of the route circuit for such route to energize in multiple selected route relays to operate the track switches as required to establish such route, and means controlled by said energized route relays for isolating the energized route circuit from the route circuits for conflicting routes irrespective of the condition of said selecting relays.

18. An entrance-exit type system for governing the power operation of track switches and the clearing of signals of a railway track layout comprising, control buttons manually operable to close entrance and exit contacts to designate entrance and exit ends of desired routes, an entrance stick relay for each entrance signal, circuit means for energizing each entrance stick relay in response to the closing of the corresponding entrance contact, a stick circuit for each entrance stick relay including in multiple a front contact of a track relay and the back contact of a track repeater relay associated with the track section next in advance of the corresponding signal, initiating circuits responsive to the energization of any given entrance relay for determining the position of certain switches to conform with all of the available routes originating at the corresponding entrance signal location, and route completion means responsive to the closing of an exit contact for a particular one of said available routes for operating the track switches to establish that route.

19. In a switch and signal control system of the entrance-exit type adapted to establish one or more through routes over successive interlocked groups and clear the entrance signal for each group in response to the actuation of manually operable buttons to designate the extreme entrance and exit ends of said through route in combination with an entrance stick relay for each entrance signal, a pick-up circuit for each entrance relay closed by manual actuation of a button to designate that signal as the entrance end of a desired route, a track circuit controlled stick circuit for maintaining each entrance relay energized until a train passes the corresponding signal, manually operable means for independently opening said stick circuit for each entrance relay for manual restoration thereof, a control circuit for each signal controlled by the corresponding entrance relay, route establishing means responsive to the operation of buttons to designate the extreme entrance and exit ends of a through route for operating the track switches in the different interlocked groups one group at a time in turn as required to provide said through route, starting with the remote interlocked group, said route establishing means acting to set up a route through each interlocked group connecting with a particular entrance signal thereof, and means responsive to the establishing of a route through each interlocked group for energizing the same entrance relay for said particular entrance

signal as if the corresponding button had been actuated.

20. A switch and signal control system of the entrance-exit type for controlling the power operation of switches and clearing of signals of a railway track layout affording one or more through routes over successive interlocked groups past one or more intermediate signals comprising, self-restoring push buttons for closing entrance and exit contacts to designate the entrance and exit end of desired routes, an entrance relay for each entrance signal energized by manual closing of the corresponding entrance contact and maintained energized until a train passes the corresponding signal, manually operable means for independently restoring each entrance stick relay, a signal clearing circuit for each entrance signal controlled by the corresponding entrance relay, an exit circuit relay associated with each signal location constituting the exit end of routes, preselecting relays associated with the switches, initiating circuits energized in response to the energization of any given entrance relay for controlling the energization of preselecting relays to condition switches in one or more interlocked groups for each of the available routes or through routes originating at the corresponding entrance signal location, said initiating circuits being effective with respect to each switch only if a path for train movement from the designated entrance signal location to and over said switch is not in conflict with some route established or occupied by a train, said initiating circuits also acting to supply operating potential to the exit relays for the exit ends of each of said available routes to permit energization thereof by closing the corresponding exit contacts, route completion means for each interlocked group responding to the energization of an exit relay thereof for operating track switches in accordance with the energized condition of said preselecting relays so as to set up a route connecting with a particular entrance signal of that interlocked group, through route control means associated with each intermediate signal in a through route and responding to the operation of said route completion means to establish a route connecting with that signal for temporarily energizing the corresponding entrance relay and also the exit relay for a connecting route in the adjoining interlocked group, and means for rendering said through route control means ineffective when the entrance relay or exit relay for corresponding signal location is energized.
21. A switch and signal control system of the entrance-exit type for track layouts affording one or more through routes over a plurality of interlocked groups past one or more intermediate signals comprising, control buttons manually operable to close entrance and exit contacts to designate the entrance and exit signal locations of desired routes, an entrance stick relay for each entrance signal location energized by manual closing of the corresponding entrance contact, a stick circuit for each entrance stick relay controlled by the track circuit next in advance of the corresponding signal, manually operable means for opening the stick circuit for each entrance relay, initiating circuits responsive to the energization of any given entrance relay for preselecting the position of switches in one or more interlocked groups to conform with all of the available routes over one or more interlocked groups originating at the corresponding entrance signal location, route completion means responsive to the clos-

ing of an exit contact at the end of a route or a through route for operating the switches in the corresponding interlocked group in accordance with the condition of said initiating circuits to establish a route connecting with a particular entrance signal for that interlocked group, through route relay means associated with each signal which may become an intermediate signal in some through route and responsive to the operation of said route completion means to establish a route connecting with that signal for energizing the corresponding entrance relay and also exercising an exit control of the route establishing means of the next adjoining interlocked group, and contact means operated by energization of said entrance relay for rendering it associated through route relay means ineffective and for disconnecting the corresponding initiating circuits from the initiating circuits of the adjoining interlocked group, whereby after a through route is established the initiating circuits and route completion means of each interlocked group involved in such through route are controlled by the corresponding entrance relay alone.

22. A switch and signal control system of the entrance-exit type for track layouts including a plurality of interlocked groups and affording one or more through routes over successive interlocked groups past one or more intermediate signals comprising, self-restoring manually operable push buttons for closing entrance and exit contacts to designate the entrance and exit ends of desired routes, an entrance relay for each entrance signal energized by manual closure of the corresponding entrance contact and maintained energized until a train passes the corresponding signal, manual control means for independently restoring said entrance relay to normal, a signal clearing circuit for each signal controlled by the corresponding entrance relay, initiating circuits responsive to the energization of any given entrance relay for preselecting the position of switches in one or more interlocked group to conform with each of the available routes or through routes originating at the corresponding entrance signal location and for rendering effective manual closure of the exit contacts for the exit ends of said routes, route completion means associated with each interlocked group and effective upon manual closure of an exit contact rendered effective by prior energization of related initiating circuits for operating switches in that interlocked group in accordance with their preselected positions and thereby establish a route through said interlocked group, and through route control means responding to the operation of said route completion means in establishing a route connecting with that signal for energizing the corresponding entrance relay and establishing a shunt for the corresponding exit contact to control the route completion means of the adjoining interlocked group, and means for rendering said through route control means ineffective when said corresponding entrance relay is energized.

23. In a switch and signal control system of the character described for track layouts including a plurality of interlocked groups for affording one or more through routes over successive interlocked groups past one or more intermediate signals, self-restoring push buttons for closing an entrance and an exit contact to designate the entrance and exit ends of desired routes, an entrance stick relay for each entrance signal adapted to be energized by closure of the corresponding entrance contact and maintained en-

ergized until a train passes the corresponding signal, initiating circuits responsive to the energization of any given entrance relay for pre-selecting the position of switches in one or more interlocked groups to conform with each of the available routes or through routes originating at the corresponding entrance signal, said initiating circuits also supplying an operating potential to the exit relays for the exit ends of said routes so that said exit relay may be energized by closure of the corresponding exit contacts, said initiating circuits including electrical connections associated with each intermediate signal in a through route, means for rendering ineffective said electrical connection for each intermediate signal when the corresponding entrance relay or exit relay is energized, and route completion means responsive to the energization of the exit relay for the end of a through route for establishing routes dependent upon the preselection effected by said initiating circuits over one or more interlocked groups involving said through route and for temporarily energizing the entrance relay for each intermediate signal in said through route and the exit relay for a connecting route of the next adjoining interlocked group.

24. In an entrance-exit type of switch and signal control system for track layouts providing through routes over successive interlocked groups past one or more intermediate signals, manually operable buttons for designating the entrance and exit ends of desired routes, route establishing means responsive to the operation of buttons to designate the extreme entrance and exit ends of a through route for operating the track switches in the different interlocked groups involved one group at a time in turn as requiring to provide said through route starting with the remote interlocked group, said route establishing means acting to set up a route through each interlocked group connected with a particular entrance signal thereof, an entrance relay for each entrance signal, means for energizing each entrance relay in response to the actuation of a button to designate the corresponding signal as the entrance end of a desired route, track circuit controlled means for maintaining each entrance relay energized until a train passes the corresponding signal, a through route control relay associated with each signal which may become an intermediate signal in some through route, an energizing circuit for each through route control relay closed only if the corresponding entrance relay is deenergized, means responsive to the operation of said route establishing means to establish a route through an interlocked group connecting with a particular intermediate signal for supplying an operating potential to the energizing circuit of the corresponding through route control relay, and contact means operated by said through route control relay for energizing the corresponding entrance relay without actuation of the corresponding button and for exercising an exit control upon the route establishing circuits of the adjoining interlocked group, said contact means being effective only temporarily until the energization of said exit relay and the exit control has been effected.

25. In a switch and signal control system of the entrance-exit type for track layouts affording through routes over successive interlocked groups past one or more intermediate signals, manually operable buttons for operating entrance and exit contacts to designate entrance and exit ends of desired routes, an entrance stick

relay for each entrance signal energized by closing of the corresponding entrance contact and automatically maintained energized until a train passes the corresponding signal, initiating circuits energized upon the energization of any given entrance relay for conditioning the track switches included in all of the available routes originating at the corresponding entrance signal for operation to positions required for said routes, route completion means associated with each interlocked group and responsive to the actuation of exit contacts thereof for operating switches in that interlocked group in accordance with the energization of the corresponding initiating circuits thereby establishing a route connecting with a particular entrance signal of that interlocked group, electro-responsive means associated with each intermediate signal in a through route and operated by the route completion means of the corresponding interlocked group only if the corresponding entrance relay is not then energized for energizing the corresponding entrance relay and for exercising an exit control upon said route completion means of the next adjoining interlocked groups, and means for restoring said electro-responsive means to normal after operation thereof when said energization of said entrance relay and said exit control has been effected.

26. A switch and signal control system of the entrance-exit type for track layouts affording one or more through routes over successive interlocked groups past one or more intermediate signals, manually operable buttons for closing entrance and exit contacts to designate signal locations to constitute the entrance and exit ends of desired routes, initiating circuits energized in response to the manual actuation of any given entrance contact for preselecting the position of track switches in one or more interlocked groups to conform with each of the available routes or through routes originating at the corresponding entrance signal location, route completion means controlled by closing of exit contacts for operating switches in accordance with the energized condition of corresponding initiating circuits and thereby establish a route or through route between the entrance and exit signal locations designated by the operation of buttons, and means for preventing energization of those initiating circuits relating to a switch in response to the manual operation of an entrance contact if a route or portion thereof occupied by a train is in conflict with the path for train movement from the entrance signal corresponding to the entrance contact operated to and over that switch in the position that would be preselected by the energization of said initiating circuits.

27. A switch and signal control system of the entrance-exit type for controlling the power operation of switches and clearing of signals in a railway track layout affording one or more through routes over successive interlocked groups past one or more intermediate signals, said track layout affording alternative through routes between said entrance and exit signal locations, said system comprising, manually operable buttons for operating entrance and exit contacts to designate the entrance and exit ends of desired routes, initiating circuits energized in response to the manual operation of any given entrance contact for conditioning the track switches in one or more interlocked groups for operation to

positions to conform with each of the routes and through routes originating at the corresponding entrance signal location, route completion means rendered effective by the manual actuation of the exit contacts for operating switches in accordance with the energized condition of the corresponding initiating circuits and thereby establish a route or through route between the entrance and exit signal locations designated by the buttons actuated, said initiating circuits relating to each crossover required to be in different positions for different alternative through routes normally acting to preselecting said crossover for operation to one predetermined position in preference to the other position upon manual actuation of the entrance contact for the common entrance end of said alternative through routes, and means for preventing the energization of said initiating circuits relating to each of said crossovers if a route or a portion thereof occupied by a train is in conflict with the alternative route over that crossover in said predetermined position, whereby the particular alternative through route to be established upon actuation of the buttons for the extreme entrance and exit ends thereof is automatically selected dependent upon train presence.

28. In a switch and signal control system of the character described for track layouts affording alternative through routes over successive interlocked groups past different intermediate signals, manually operable buttons for closing entrance and exit contacts to designate entrance and exit ends of desired routes, a preselecting relay means for each switch, initiating circuits energized in response to the manual operation of any given entrance contact and normally acting to energize the preselecting relay means relating to the trailed switches in one or more interlocked groups for each of the routes or through routes originating at the corresponding entrance signal location, thereby preselecting said trailed switches for operation to a predetermined position in preference to the other position, said initiating circuits also rendering effective manual actuation of exit contacts belonging to the exit ends of said route, completion circuits energized by the actuation of an exit contact rendered effective by the energization of the corresponding initiating circuits for operating switches in accordance with the condition of the corresponding preselecting relay means and thereby establish a route or through route between the entrance and exit signal locations designated by the buttons actuated, and means for preventing energization of the preselecting relay means for each of said trailed switches if a route or portion thereof occupied by a train conflicts with the path for train movement to and over that switch in said predetermined position, whereby actuation of buttons for the extreme ends of alternative through routes normally establishes a preferred route but automatically establishes another of the alternative through routes if some route occupied by a train conflicts with said preferred route.

29. In a switch and signal control system of the entrance-exit type described, a track layout including crossovers connecting parallel tracks and providing two optional routes between the same signal locations for train movement in both directions, manually operable contact means for designating said signal locations as the entrance end or the exit end of said optional routes, route selecting means responsive to the actuation of

said contact means to designate either one of said signal locations as the entrance end of said optional routes for train movement in one direction or the other for preselecting the positions of said crossovers to establish the same optional route if available in preference to the other optional route, and route establishing means responsive to the actuation of said contact means to designate an exit signal location following the designation of an entrance signal location for operating said crossovers in accordance with the positions preselected by said route selecting means.

30. In a switch and signal control system; a plurality of interlocked groups located end-to-end and each including a plurality of track switches for setting up different routes and through routes over said interlocked groups with signals for governing traffic over such routes, said interlocked groups also including detector track sections associated with said track switches, manually operable contact means for each of said signal locations; an entrance relay for each of said signal locations; pick-up circuit means for each of said entrance relays energizable by its associated manually operable contact means; stick circuit means for each of said entrance relays energized dependent upon the unoccupied condition of the detector track section immediately in advance of its associated signal; a circuit network for each of said interlocked groups conforming to the track layout of its group, said circuit networks for adjacent interlocked groups being normally connected at points corresponding to the adjacent portions of track; means controlled by each entrance relay for applying energy to said circuit network at a point corresponding to its signal location which energy is permitted to flow over all available routes emanating from that signal location throughout all of the interlocked groups; an exit relay for

each exit end of a route connected to said circuit network at the corresponding point and controlled by its corresponding manually operable contact means, whereby the actuation of a 5 manually operable contact means for an exit end of an available route following the actuation of a manually operable contact means for entrance end causes the energization of the associated exit relay; route establishing means for 10 each interlocked group responding to the energization of an exit relay for establishing a route over that interlocked group in accordance with the energized condition of said network, said route establishing means acting to set up that route, if available, which includes a switch in 15 the normal position in preference to the reverse position, automatic circuit means associated with each signal location which may become an intermediate signal location in some through route 20 and rendered effective by the operation of said route establishing means to set up a route in advance of that signal as part of a through route for causing the energization of the entrance relay at that point the same as if a manually operable contact means had been operated for that entrance point, circuit means effective upon the picking up of an entrance relay by said automatic circuit means for picking up the exit relay for 25 the adjacent route next in the rear of such entrance point, and circuit means effective upon the picking up of any given exit relay by said automatic circuit means for opening the interconnection between the circuit networks for the adjacent interlocked groups and for restoring 30 said automatic circuit means to normal, whereby a route can be established by the actuation of any given entrance button and any given exit button in the same interlocked group or in any 35 subsequent interlocked group.
